UNITED STATES PATENT OFFICE.

ROBERT A. GALLY, OF CINCINNATI, OHIO, ASSIGNOR TO THE BALDWIN COMPANY, OF CINCINNATI, OHIO.

PNEUMATIC ACTION.

1,285,975.

Specification of Letters Patent. Patented Nov. 26, 1918.

Application filed September 25, 1917. Serial No. 193,177.

To all whom it may concern:

Be it known that I, ROBERT A. GALLY, a citizen of the United States, residing at Cincinnati, in the county of Hamilton and 5 State of Ohio, have invented certain new and useful Improvements in Pneumatic Actions, of which the following is a specification.

Prior devices for setting a pneumatically 10 controlled movement to a certain position or locked condition and releasing or returning from the said position or condition by another control element or impulse, have included such structures as the pneumatic 15 organ swell of Skinner, #500,040, June 20, 1893; the expression adjuster, lock and release of M. Gally, #329,304, October 27, 1885; the pedal control action of Hedgeland #638,709, December 12, 1899; the catch action of Brand, #835,777, November 13, 1906; and the pneumatic lock of Welte-Bockische, #1,008,291, November 7, 1911, the latter patent being especially designed 20 for the control of the air tension changes 25 for a pneumatic piano device, including means for varying the speed of movement of the controlling pneumatics.

The control of a pneumatic to different speeds of movement is not only shown in 30 the said Welte-Bockische patent, being there accomplished by two valves r^1 , r^3 , connected by two tubes z and p to a pneumatic e , but in patents of prior application dates, namely Brand #833,995, October 23, 1906, application 35 filed October 26, 1900, and R. A. Gally, #1,101,919, June 30, 1914, application filed May 11, 1903, a plurality of air service valves to one pneumatic had been employed, and prior to all these dates a plural service 40 to a motor pneumatic to vary its speed of operation had been made and sold by this applicant, the same party as the applicant for said Patent #1,101,919, having been set forth by affidavits filed in the file of application #156,623; from which the said Patent #1,101,919 was issued. In the present invention the locking action is secured by a sliding **D** valve having two pneumatic motors to actuate the said valve, one motor to 45 move it to active service, the other to return it to inactive condition. While a **D** valve moved by a pneumatic is very old, as in O. H. Needham, #250,833, December 13, 1881, only one pneumatic was employed to 50 operate that **D** valve, and a spring caused 55

the immediate return of the valve when that one pneumatic was relieved, and although Philipps #1,115,735 has a **D** valve moved in two opposite directions by two actuating pneumatics, his said valve is normally at 60 median position, his two actuating pneumatics are adapted to act together when his two control apertures open at the same time, as they do when his two music sheets are in 65 perfect synchronism, and he has three ports controlled by his valve, and two pneumatic motors served thereby, whereas in the present invention the valve is normally at one end or the other of its movement, the two actuating pneumatics always act separately, 70 and there are only two ports serving only one motor pneumatic.

In the present invention the two speeds of movement of one element of an apparatus operated by a pneumatic means is accomplished by the use of two pneumatics operatively connected to the one said element, one of the said pneumatics having a different speed of air service actuating it than that of the other said pneumatic, but 75 both said pneumatics adapted to move the said element in the same direction.

In the drawings, Figure 1 is an elevation, partly sectional, showing the locking devices, and the varied speed control movement, including a floating member assisting the obtaining of extra degrees or speeds of movement; while Fig. 2 is a modified form 80 without a floating member, and Fig. 3 a plan view of the arms, rod and lug of Fig. 2. 90

In our main showing, Fig. 1 there is a movable element 1, which may be the means of performing or controlling any desired movement or operation. To this element 1 is pivoted by a pivot 3, a floating lever 2 95 extended in both directions from the pivot 3, and having at each end of said lever 2 a connecting rod or wire 4, 5, each rod 4, 5, connected at its other end to a corresponding pneumatic 6, 7, the collapse of 100 either one of these two pneumatics 6, 7, causing the same direction of movement of the element 1 as indicated by the arrow therewith. As one pneumatic may be provided with a different tension, rate of air 105 service than the other, it is thereby possible to have two speeds of movement of the element 1 according to which of the two pneumatics 6, 7, is actuated, and by the action of both the two pneumatics at one time the 110

added power of the two would cause a third degree of speed of movement of the element 1. While two pneumatics to actuate one element is old, as in Clark #1,014,949, January 5 16, 1912, filed May 12, 1909, and a different air tension was connected to each of the two pneumatics, that use only accomplished one length of stroke of his moving element, the key B, whether one or the other pneumatic 10 was actuated or both together.

In the present showing the different speeds of action of the two pneumatics 6, 7, are secured by the different size of air service channels 8 and 9 leading from their respective pneumatics 6, and 7, to the valves 10 and 11 controlling the service and return flow of air of the two pneumatics 6, 7. The two pneumatics 6, 7 might be different in size, or of their leverage, to the element 1, 15 and thereby secure a differing speed from an equal capacity or tension service, or such varied size or leverage of pneumatic be combined with measures of securing a varied power of movement of the element 1, and yet 20 be of the gist of the present invention. Also, the floating member 2 may be omitted, and the two pneumatics 6, 7, disposed to act in some other manner, as for instance as in Figs. 2 and 3, by the direct action from the 25 pneumatics 6, 7, by arms 12, 13 engaging directly under a lug 14 on the movable element 1', and the different air capacities of service to the two pneumatics 6, 7, secure different speeds of movement according to 30 which one or both of the said pneumatics are actuated at one time and by employing checks 22, 23, or other suitable means, the extent of movement of each pneumatic can be made of a fixed or regulated degree, and one 35 such degree different to the other, or of equal amounts, as may be desired. For control of the two pneumatics 6, 7, to different speeds under any of the above stated conditions, any style of valves may be used in lieu of the 40 slide valves 10, 11 now shown, but these slide valves are especially desirable for the securing of a simple and certain means of locking a pneumatic to active or inactive position, as will now be described.

45 Each slide valve 10, 11, is of the D type, and has a chamber 15 adapted to connect the port of the channel 8 or 9 to the air service 16, 17 of the apparatus whenever either valve 10, or 11 is slid to its active position by means of a primary pneumatic 18 or 19 or other initiating force, as shown by valve 11 and primary pneumatic 19. The same 50 valves 10, 11 are adapted to release the air inside of the corresponding pneumatics 6, 7, when either such valve is slid to the inactive 55 position by means of a primary pneumatic 20 or 21, as shown by valve 10 and primary pneumatic 20, the outer ends of channels 8 or 9 acting as relief ports for the release of 60 pneumatics 6 and 7. The several primary

pneumatics 18, 19, 20 21, may be connected by ducts 24, 25, 26, 27, leading to manual valves or the apertures of a tracker bar, or to any other initiative or intermediate control, and more than one slide valve may be 70 connected to a pneumatic as 6, 7, and the slide valves may be moved by other forms of primary pneumatics than the pouch style now shown, or the slide valves may be moved by any other power, as mechanical, or by 75 electromagnets, and various other modifications made, and yet the structure be subject to:—

What I claim as my invention, is:

1. A movable element, a lever connected to 80 the said element intermediate the length of the said lever, and two pneumatics, one said pneumatic connected to the said lever at one side of its connection to the said element, and the other said pneumatic connected to 85 the said lever at the other side of the said connection, and means adapted to cause the operation of either one of the said pneumatics at will.

2. A movable element, a lever connected to 90 the said element intermediate the length of the said lever, and two pneumatics, one said pneumatic connected to the said lever at one side of its connection to the said element, and the other said pneumatic connected to 95 the said lever at the other side of the said connection, and means adapted to cause the operation of either one of the said pneumatics at will; and both the said pneumatics adapted to operate the said element in the 100 same direction.

3. A movable element, a lever connected to 105 the said element intermediate the length of the said lever, and two pneumatics, one said pneumatic connected to the said lever at one side of its connection to the said element, and the other said pneumatic connected to the said lever at the other side of the said connection, and means adapted to cause the operation of either one of the said pneumatics at will; and to cause the operation of 110 both said pneumatics at one time.

4. A movable element, a lever connected to 115 the said element intermediate the length of the said lever, and two pneumatics, one said pneumatic connected to the said lever at one side of its connection to the said element, and the other said pneumatic connected to the said lever at the other side of the said connection, and means adapted to cause the 120 operation of either one of the said pneumatics at will, and to cause the operation of both said pneumatics at one time, both the said pneumatics adapted to operate the said element in the same direction.

5. A movable element, a lever connected to 125 the said element intermediate the length of the said lever, and two pneumatics, one said pneumatic connected to the said lever at one side of its connection to the said element,

and the other said pneumatic connected to the said lever at the other side of the said connection, means adapted to cause the operation of either one of the said pneumatics at will, and means adapted to cause the operation of both said pneumatics at one time, the said operation of both pneumatics at one time moving the said movable element to a greater distance than the operation of the 10 said element by either one of the said pneumatics by itself.

6. A movable element, a lever connected to the said element intermediate the lengths of the said lever, and two pneumatics, one 15 said pneumatic connected to the said lever at one side of its connection to the said element, and the other said pneumatic connected to the said lever at the other side of the said connection, and means adapted to cause the 20 operation of either one of the said pneumatics at will, and to cause the operation of both said pneumatics at one time, both the said pneumatics adapted to operate the said element in the same direction, the said operation 25 of both pneumatics at one time moving the said movable element to a greater distance than the operation of the said element by either one of the said pneumatics by itself.

7. A movable element; two pneumatics; operative connections from the said pneumatics to the said element; each said pneumatic movable in the same direction but mechanically limited to different distances 30 one to the other, and means adapted to induce the operation of each said pneumatic separately from the other said pneumatic.

8. A movable element; two pneumatics; operative connections from the said pneumatics to the said element; each said pneumatic movable in the same direction but mechanically limited to different distances one to the other, and means adapted to induce the operation of each said pneumatic 40 separately from the other said pneumatic; or to induce the operation of both said pneumatics together.

9. A movable element; two pneumatics; operative connections from the said pneumatics to the said element; each said pneumatic movable in the same direction but mechanically limited to different distances one to the other, and means adapted to induce the operation of each said pneumatic 50 separately from the other said pneumatic; and means adapted to check the throw of one said pneumatic to a different amount of movement of the said movable element than the movement of the said element by the 55 other said pneumatic.

10. A movable element; two pneumatics; operative connections from the said pneumatics to the said element; each said pneumatic movable in the same direction but 60 mechanically limited to different distances

one to the other, and means adapted to induce the operation of each said pneumatic separately from the other said pneumatic; and means adapted to check the throw of one said pneumatic to a different amount of 70 movement of the said movable element than the movement of the said element by the other said pneumatic.

11. A sliding D valve; a pneumatic adapted to move the said valve in one direction 75 and one certain distance only, and another pneumatic adapted to move the said valve in the opposite direction and the same certain distance only; a service port and a single relief port only, both said ports controlled by the said valve; and a single other pneumatic having direct and constant connection to the said relief port.

12. A valve; a pneumatic adapted to move the said valve in one direction and in one 85 certain distance only, and another pneumatic adapted to move the said valve in the opposite direction and the same certain distance only; the said valve and pneumatics adapted to a position of rest of the said 90 valve at the end of its movement of the one certain distance only in either direction and with both said pneumatics inactive at such times of rest of the said valve; a service port and a single relief port only, both said 95 ports controlled by the said valve; and a single other pneumatic having direct and constant connection to the said relief port.

13. A slide valve; a pneumatic adapted to move the said valve in one direction and one 100 certain distance only, and another pneumatic adapted to move the said valve in the opposite direction and the same certain distance only; a service port and a single relief port only, both said ports controlled by the 105 said valve; and a single other pneumatic having direct and constant connection to the said relief port.

14. A slide valve; a pneumatic adapted to move the said valve in one direction and in 110 one certain distance only, and another pneumatic adapted to move the said valve in the opposite direction and the same certain distance only; the said valve and pneumatics adapted to a position of rest of the said 115 valve at the end of its movement of the one certain distance only in either direction and with both said pneumatics inactive at such times of rest of the said valve; a service port and a single relief port only, both said 120 ports controlled by the said valve and a single other pneumatic having direct and constant connection to the said relief port.

15. A sliding D valve; a pneumatic adapted to move the said valve in one direction 125 and one certain distance only, and another pneumatic adapted to move the said valve in the opposite direction and the same certain distance only; a service port and a single relief port only, both said ports con- 130

trolled by the said valve; and a single other pneumatic having direct and constant connection to the said relief port.

16. A sliding **D** valve; a pneumatic adapted to move the said valve in one direction and one certain distance only, and another pneumatic adapted to move the said valve in the opposite direction and the same certain distance only; the said valve and pneumatic adapted to a position of rest of the said valve at the end of its movement of the

one certain distance only in either direction and with both said pneumatics inactive at such times of rest of the said valve; a service port and a single relief port only, both said ports controlled by the said valve; and a single other pneumatic having direct and constant connection to the said relief port. ¹⁵
